UNITED STATES PATENT OFFICE.

DANIEL GOLDSMITH, OF NEW YORK, N. Y.

DESIGN FOR A GEM FOR FINGER-RINGS.

SPECIFICATION forming part of Design No. 15,205, dated August 5, 1884.

Application filed November 1, 1883. Term of patent 3½ years.

To all whom it may concern:

Be it known that I, DANIEL GOLDSMITH, of the city, county, and State of New York, have invented and produced a new and original Design for Gems for Finger-Rings, of which the following is a full, clear, and exact description.

Reference is to be had to the accompanying drawings, forming part of this specification, in which similar letters of reference indicate corresponding parts in all the figures.

Figure 1 is a face view of my newly-designed gem for finger-rings. Fig. 2 is an edge view, and Fig. 3 is a face view with a monogram attached thereto.

The gem A is of a generally flat configuration, with its face of a series of parallel planes or face-sections at an obtuse angle to each other, with each plane or face section of equal length, and extending the full length of the gem or stone. As shown, the middle plane, a, is at right angles to a diameter passing through the middle of the setting, and the other planes, b b, bevel therefrom at an equal inclination.

If desired, my design can receive a mono-

gram or initial, as in Fig. 3, which may be applied to or engraved on it without destroying the characteristic feature of the design.

Having thus described my design, what I claim as new is—

1. A design for a finger-ring gem, consisting of a single solid gem or setting having its face wrought into flat parallel planes or facets arranged at an obtuse angle to each other and of equal length, as shown and described.

2. A design for a finger-ring gem, consisting of a flat solid and single setting having a middle plane at right angles to a diameter of the ring passing through the center of the setting, and two side planes beveling from the middle plane at an equal obtuse angle, all of said planes being of equal length and extending the full distance between the opposite walls of the gem-frame, as shown and described.

DANIEL GOLDSMITH.
